UNITED STATES PATENT OFFICE.

FREDERICK H. DANIELL, OF FRANKLIN, NEW HAMPSHIRE, AND JOHN C. HEBDEN, OF PROVIDENCE, RHODE ISLAND; MARY B. DANIELL EXECUTRIX OF SAID FREDERICK H. DANIELL, DECEASED.

PACKAGING YARN FOR DYEING.

974,127.

Specification of Letters Patent.

Patented Nov. 1, 1910.

Application filed September 14, 1908. Serial No. 452,960.

To all whom it may concern:

Be it known that we, FREDERICK H. DANIELL, a citizen of the United States, and resident of Franklin, New Hampshire, and 5 JOHN C. HEBDEN, a citizen of the United States, and resident of Providence, Rhode Island, have invented certain new and useful Improvements in Packaging Yarn for Dyeing, of which the following is a specification.

Our invention relates to the support of masses of yarn so as to permit the ready passage of dyeing or mordanting liquids and gases through the masses without materially disturbing the relation of the coils of winding or distorting of the form of package and has reference to the class of devices set forth in the application of F. H. Daniell, Serial No. 417,419, filed February 24, 1908. 15 To this end, the invention consists in forming a yarn package about a hollow holder or support of such character as to properly hold the mass in shape and preserve the relation of the windings; while 20 capable of axial or longitudinal compression to permit a number of packages to be held together under pressure with their ends abutting; and with openings or channels for the passage of the liquor to or from the 25 rounding yarn masses, as fully set forth hereinafter and illustrated in the accompanying drawings, in which:—

Figure 1 is a sectional view showing one form of yarn package embodying my improvement; Fig. 2, a view showing a modified form of holder or support for the package with end flanges, similar to a spool; Fig. 3, a transverse sectional view of the latter, showing the construction of the tube 40 or barrel of the spool; Figs. 4, 5, 6, 7, 8, views showing further modifications in the structure of the holder; Fig. 9, a transverse sectional view of Fig. 8; Fig. 10, is a view of still another modification.

It is advantageous to dye or similarly treat yarn in commercial packages of large volume in order that the yarn may be economically handled in shipping and in transferring it in manufacturing processes, such 45 as twisting, knitting, warping, etc. It will be obvious that it is desirable to have the yarn in as long lengths as possible, to avoid tying it up in the making of thread or 50 fabric, and the present form of cop or package provides a much greater length than 55 in skeins, hanks, chains or mule cops.

The usual method has been to dye yarn in the skein, hank or chain, and, in some cases, it has been dyed in the mule cop; but heretofore, attempts to dye yarn in packages 60 of considerable bulk have not been entirely successful. It has been found difficult to secure an even and thorough permeation of the dye liquor throughout the whole mass, which is necessary to secure an even color, 65 and it has also been found practically impossible to retain the cop in its original conformation, after the dyeing, so that the yarn can be subsequently unwound without snarling or breaking. To obviate these difficulties, we first form a holder or support which is capable of properly supporting the mass 70 of yarn, but which has the capacity to yield longitudinally under pressure, and which will also permit the lateral passage of the 75 liquid or gas to be applied to the yarn.

As shown in Fig. 1, the yarn mass is represented in section at A as wound into a cylindrical package supported on the holder or tube B. The tube B consists of two spirally wound, openly coiled, flat, perforated bands b and b², of any suitable material, preferably a non-corrosive metal, arranged with the band b² inside the band b and with their edges overlapping. The band b² closes 85 the space between the coils of the band b so that a continuous tube is formed. Preferably, the bands are held together at the ends of the tube by the ferrules or rings c—c 90 which are riveted or otherwise suitably fastened to the ends of the bands to make them both integral in the tube. This structure gives a light durable tube with a substantially regular exterior surface on which the 95 yarn can be wound; and capable of being longitudinally compressed, but resisting any tendency of the cop to collapse under the construction of the winding or form shrinkage of the mass in dyeing. The perforations are sufficient in number to give ample 100 vent to the liquor or gas to allow it to be forced radially outward from the tube into the material; or to provide for forcing it from the outside of the cop through the mass and into the tube.

In Fig. 2 is shown another method of

forming the tube of helically wrapped bands. In this modification, the inner band d closes the space between the coils of the outer band d^2 and is fluted or crimped, as shown in the sectional view, Fig. 3, the flutes providing passages for the flow of the liquid or gas between the bands. In this construction it is not absolutely necessary to have the outer band d^2 perforated, although it is so shown. Again, the inner band might also be perforated to give a still freer flow for the dyeing solution, if required. In this embodiment, we have shown flanges e — e secured at the ends of the tube to make it a spool, such flanges being necessary for some methods of winding. In Fig. 4 is shown another different method of forming the tube of spirally wrapped bands, one inside the other, but in this case the bands are narrower and the outer coils are of opposite pitch from the inner ones, the coils crossing each other diagonally to form a sort of lattice-work. Preferably, four coils are employed, two, g and h , wound in one direction, parallel to each other, each coil being wound open a distance about equal to its width, and two, i and j , wound in the same manner in the opposite direction and of slightly less diameter. The coils i and j fit inside the coils g and h and the ends of all of the coils are fastened to the rings k — k , the whole forming a latticed tube capable of axial contraction and having multiple apertures for the flow of the dyeing fluid or gas. The crossing of the bands prevents the coils of yarn from being drawn down between them, beyond the circumference of the tube, so that a diametrically rigid core is provided to support the mass. In Fig. 5, a longitudinally sectional view, the band l is formed with laterally extending lugs or teeth m , n , etc., which intermesh when the band is wrapped helically as shown. The purpose of these lugs is to provide a support for the coils of yarn in the winding to prevent them from drawing down between the coils of the tube. They have the additional advantage of acting as a limit to the contraction of the tube by engaging the edges of the band when the tube is compressed longitudinally. The lugs also prevent accidental distortion of the tube by locking together if the tube is untwisted or stretched out beyond its normal length. As will be readily perceived, the spaces between the lugs give ample vent for the liquid or gas used in dyeing and the tube has the essential capacity of being contractible along its axis. Fig. 6 illustrates in section, a tube constructed of helically coiled wire netting or screen n . This might be made of a single band, wrapped upon itself with overlapping edges, or of two coiled bands one overlapping the other. The screen provides for un-

restricted flow of the fluid from the tube to the yarn or vice versa, and the coiling of the band allows the required axial contraction of the tube.

Fig. 7 shows a modification in which a perforated band o is substituted for the netting and arranged in the same manner to provide for axial contraction.

In Fig. 9, we have shown a telescopic tube in two sections, r and s , with the overlapping portions fluted along the tube, as shown in section in Fig. 10, the two parts being suitably perforated for the passage of the liquid or gas. It will be understood that the section r slides on the section s to allow the tube to be contracted longitudinally.

Fig. 11 shows a tube composed of three sections— t , u and v —the end sections t and v adapted to slide on the middle section u and each formed with perforations as shown.

The yarn is wound upon the tube or holder in any suitable manner, preferably by the "Universal" system of winding, which gives a regular disposition of the coils and therefore a more uniform density of the yarn mass, and which provides for building flat-ended packages. As shown in Fig. 1, it is desirable to have the tube project slightly beyond the ends of the package to prevent the end coils from falling over the ends of the tube when the package is subjected to rough usage. The packages thus formed are placed end to end and forced together longitudinally, the abutting holders yielding sufficiently to permit the ends of the packages to be brought closely together to form one continuous tubular mass of yarn, so that when liquor or gas is forced into the associated holders it will be compelled to pass through the yarn, while the latter will be properly supported with all of the packages compressed to a uniform density.

For convenience in handling, it is preferable to arrange the cops in units, with from three to six, or more, cops in each unit. A number of units are then placed in the dyeing chamber, as many as it will accommodate, and all of the cops subjected to the dyeing or other process at one time.

The manner of supporting the units and compressing the cops is fully described and illustrated in our pending application, Serial No. 427,379, filed April 16th, 1908, and need not here be more fully described since we do not herein claim the apparatus or method for treating the cops.

Our improvement consists in packaging yarn on longitudinally contractible, previous holders to provide for compressing a series of the cops or packages into one continuous tubular mass to be dyed or similarly treated by a circulating process; and, after such treatment, the packages will return to their normal conditions, so as to be available for commercial uses without further handling.

Without limiting ourselves to the precise construction of the cop tubes or holders described, what we claim is:

1. A cop tube adapted to carry cops of 5 yarn which consists of a spirally wound and perforated band capable of being longitudinally compressed and with its walls pervious to the flow of liquid or gas.
2. An improved support for yarn pack- 10 ages for use in dyeing or similar processes consisting of a tube formed of a spirally wrapped band, adapted to be compressed longitudinally of its axis and having its walls pervious to the flow of liquid or gas.
3. An improved support for yarn pack- 15 ages consisting of a tube comprising correlated sections adapted to move in relation to each other to allow the tube to be compressed longitudinally of its axis, and having its walls pervious to the flow of liquid or gas. 20
4. A cop tube adapted to carry cops of yarn comprising perforated resilient material, the portions of which are movable with relation to each other, whereby the tube is adapted to be compressed longitudinally of 25 its axis and has its walls pervious to the flow of liquid or gas.

In testimony whereof we affix our signatures in presence of two witnesses.

FREDERICK H. DANIELL.
JOHN C. HEBDEN.
